UNITED STATES PATENT OFFICE.

YORKE BURGESS, OF CHICAGO, ILLINOIS, ASSIGNOR TO HOPKINS M. LOUDON, OF KANSAS CITY, MISSOURI.

AUTOMATIC SYSTEM FOR STOPPING TRAINS.

1,411,078.

Specification of Letters Patent. Patented Mar. 28, 1922.

Application filed November 13, 1919. Serial No. 337,699.

To all whom it may concern:

Be it known that I, YORKE BURGESS, a citizen of the United States, residing at Chicago, in the county of Cook and State of Illinois, have invented certain new and useful Improvements in Automatic Systems for Stopping Trains, of which the following is a specification.

One of the objects of the invention is to provide an automatic system for stopping a train when conditions are present that would render further progress dangerous.

Another object is to provide automatic train stopping means in cooperation with the visual signal system, compelling cessation of train movement upon the occurrence of a visual signal to that effect.

Another object is to provide a system and apparatus which, in connection with a system of fixed, block and interlocking signals, will automatically apply the brakes if the engineer fails to obey the signal indication.

Another object is to provide a system which will automatically apply the brakes of the train if the visual signal fails to indicate the condition requiring application of the brakes.

Another object is to produce an automatic train stopping system in which all of the parts are on a constant test, and which will go to safety and stop the train if there is an extraneous break, cross or ground in the circuit, or other failure of electric energy in the signal system or any defects in the mechanical construction.

Another object is to provide a system in which the brakes cannot be released after being automatically set until the train has been brought to a full stop.

Another object is to provide a system controllable only through a selected locomotive, when two or more locomotives are connected to the same train.

Another object is to provide a system which is operable when the locomotive is moving forwardly or rearwardly.

Another object is to provide a system for stopping a train which will not interfere with the visual or interlocking signals, when the latter indicate safety, and which will not perform its desired function at that time.

Other further and more specific objects of the invention will become readily apparent, to persons skilled in the art in considera-

tion of the following description, when taken in conjunction with the drawings wherein:—

Fig. 1 is an elevation of a locomotive showing a part of the apparatus, included in the system, attached thereto.

Fig. 2 is an enlarged view of the tender of the locomotive showing part of the apparatus in end elevation.

Fig. 3 is a diagrammatic view of an air line of a locomotive adapted to operate the signals.

Fig. 4 is a similar view of the air line of the second locomotive attached to the same train and disabled from operating signals.

Fig. 5 is an enlarged sectional view of a three way valve used on the locomotives in the air line.

Fig. 6 is a side elevation of the contact rail placed along the track and adapted to impart current to the train stopping mechanism located upon the locomotive.

Fig. 7 is an enlarged perspective view of a part of said rail and one of its supports.

Fig. 8 is a cross-section of the same.

Fig. 9 is a side elevation of the mechanism used to automatically open the air line to stop the train.

Fig. 10 is enlarged detail sectional view taken on line 10—10 of Fig. 9.

Fig. 11 shows the relative position of the contact rail, indicated in Figure 6, with reference to the stopping mechanism shown on Fig. 9, when the latter is about to mount the rail.

Fig. 12 is a diagrammatic view of a circuit used for operating the usual visual signals and semaphores.

Fig. 13 is a diagrammatic view of the circuits necessary for my stopping mechanism, shown in connection with the visual signal system illustrated in Fig. 12.

In all the views of same reference characters are employed to indicate similar parts.

The train stopping mechanism for automatically opening the air line to apply the brakes, is indicated by 20 shown connected to the tender 21 of the locomotive; the engine portion 22 being connected to the tender by the usual flexible connections for the air line 23. The air line section 24 is shown associated with the tender and the air line section 25 is shown associated with the engine of the locomotive. These portions of the air line are shown broken in two, to in-

dicate that they may extend a further distance than shown diagrammatically in Figures 3 and 4. In Fig. 3 the air line is the one which controls the train while in Figure 4 the valves are shown set in such way as to disable the second locomotive with respect thereto but to preserve the air line complete through the second locomotive for the purpose of controlling the train by the 10 first locomotive. The stopping mechanism 20 consists of a frame 26 supported on the plate 27 which depends from the tender 21 of locomotive, and secured thereto by means of bolts 28 passing through the flange 29 and 15 by nuts 30. The frame 26 is provided with an upturned bracket portion 31, having a central hub 32 for a bearing, for a vertically movable tube 33. Another hub 34 serves as a guide for the tube and is secured to a 20 cross-piece 35. The tube 33 extends to the shoe 36 and is secured thereto as shown in Fig. 10, by a flange 37 and screws 38. The shoe 36 is held in proper position by means of links 39 that are pivoted thereto and are 25 provided in their upper ends with elongated slots 41, that receive a headed bolt 42.

Now, from the foregoing description it will be manifest that the tube 33 may be moved vertically in the bearings 32 and 34, 30 and that the links 39 will hold the shoe in the aligning position shown during such movement; the slots 41 permitting the upward movement of the shoe. The spring-pressed brushes 43 may be secured to the 35 frame and serve for brushing off the upper surface 44 of the contact rail 45.

The frame 26 is insulated from the downwardly depending plate 27 by bolts 46 so that the electric current may pass from the 40 contact rail 45 to the shoe 36 and through the solenoid or electro-magnet 47, by wire 48 and then to the ground or frame of the locomotive, as at 49.

A link 50 is pivoted to the vertical tube 33, 45 as at 51, and also to the lower end 52 of the armature support 71 of the solenoid 47. This link, 50, is also pivoted to the frame 26, as at 54, so that when the shoe 36 is raised, the core support 71 in guide 70 is positively 50 moved downwardly leaving the core 53 in its elevated position when the solenoid is energized and the core 53 is such that when the solenoid 47 is electrically energized, the core 55 will be pulled upwardly thereby and lift the weighted lever 54. When the shoe 36 is in its lower position, as shown in Fig. 9, it supports the lever 54 in a horizontal position, because it positively lifts this lever through the core 53 and its support 71. The lever is 60 pivoted as at 55 and is provided with an outward weighted end 56, immediately above the nonmagnetic attachment 53' to the core 53, so that when the support 71 of the core is removed, the lever will take the dotted line 65 position shown in Fig. 9. The weight 56, of

the pivoted lever 54, is sufficient to raise its latch end 57 when the solenoid 47 is not energized, so that the lever 54 will never be in its horizontal position if current is withdrawn from the solenoid during the time 70 when the shoe 36 is resting on the contact rail 45. The front end 57 of the lever serves as a latch to hold a valve lever 58 in position as shown in full lines in Fig. 9. The front end of the valve lever 58 is provided 75 with a valve portion 59 which normally closes a port in the end of the tube 60. The lever 58 is pivoted, as at 61, and is provided with a weighted part 62 so that when it is unsupported it will fall away from the position shown in full lines in Fig. 9, in which position it closes the port in the tube 60. The latch lever 54, supports the valve lever 59 in its operative position and when the latch lever is raised to dotted line position, 80 the valve lever 58 will fall from the position in which it is normally supported into the dotted line position, thereby opening the port in the tube 60. The tube 60 is connected by conduit 62, to the upper end of the 85 vertically movable tube 33 as at 63. It is also connected to the air line branch 64 of the locomotive, by means of the conduit 65. The air line branch 64 is connected at each end of the locomotive, to the main air line 90 24-25. The main air line, at each end of the locomotive is provided with a three way valve 66, shown more clearly in Fig. 5. The valve 66, at the front 67 of the engine, shown in Fig. 3, is closed, but it permits open communication with the branch line 64, while the valve 66, at the rear end of the tender of the locomotive is open, with respect to the main air line, but it is closed with respect to the branch 64. Now, if the engine is moving rearwardly, the valve 66 in the rear of the tender should be opened, or it would occupy the position shown with respect to the valve 66 in the front of the engine, and this valve would occupy the position shown by the valve in the rear of the engine so that the locomotive may operate in either direction with respect to my stopping mechanism. The ordinary two-way 100 valves, as 68, are to be employed as usual, in the air line at the front of the tender and rear of the engine, respectively. Now, in looking at Fig. 4, it will be seen that the second engine would be incapacitated because the branch air line 64 is entirely shut 105 off from the main air line 24-25 at both of its terminal ends.

Now, from the foregoing information, it will be manifest, to persons skilled in the art that if the solenoid 47 be demagnetized, 115 when the shoe 36 is raised upon the top surface of the rail 44, that the core 53 will move downwardly in the guide 70, (which is a tube within the solenoid 47) inasmuch as its support 71 has been withdrawn by the down- 120 130

ward movement of the end 52 of the lever 50 thereby causing the weighted lever 54 to move down to the dotted line position, and unlatch the valve lever 58, thereby opening 5 the port in the tube 60 and opening the air line, whereby the brakes of the train will be applied. The core 53, of the solenoid 47, supports on its upper end a piece of non-magnetic material 53' such as brass, or the 10 like, and the core 53 is supported at its lower end by the vertically moving part 71, which is connected to the outer end of the pivoted lever at 50. When the shoe 36 is not in raised position, as when it is not on the top 15 surface 44 of the contact rail 45, the weighted lever 54 will be mechanically and positively held at its elevated position, thereby holding the valve lever 59 to close the air line. At this time, of course, the solenoid 20 47 will be deenergized because it receives current only when the shoe is on the top surface of the contact rail 45.

The contact rail 45 has in its construction, preferably, two lateral webs 73 and 74, and 25 a vertical leg 75, the latter being insulatedly supported in the support 76, as at 77. The contact rail is held in the position shown in Fig. 6 by a series of the supports and by bolts 79 that are passed through the supports. 30 The supports are spaced apart along the longitudinal dimensions of the contact rail, and each support is provided with a definitely located, relatively small cross-sectional area, by the transverse slots 80, so that if a support breaks at any point, it will break at this, the weakest point in the structure. The upper surface 44 of the rail is, preferably, made of a sheet of aluminum secured at the side of the webs 73 and 74, as by 35 screws 81. The aluminum provides a surface that will not rust and which will make ready contact with the shoe 36 of the stopping mechanism 20.

To indicate danger, in event of breaking 40 of any of the standards 76, a circuit is made through the series of standards or supports by the wire 82, connected to the upper end of the first standard, as at 83, and then to the lower end of the next standard, as at 84, 45 and so on throughout the series of standards, so that the attenuated parts between the transverse slots 80 will be in series in the circuit. Now, in event of any of the standards breaking between the transverse slots 50 80, the circuit just described will be thereby opened, so that when the shoe 36 rides upon the contact rail, the electro-magnet 47, having lost its current, the latch lever 54 will move downwardly and release the valve 55 lever 58, thereby opening the air line and applying the train brakes, at the same time the visual signal will be set in the next block 60 in the manner to be hereafter described.

In Fig. 12 is shown the usual visual signal 65 system, showing the track divided into two

blocks and showing the mechanism common to one block. There is at each end of the block a semaphore 90, held in safety position by an electro-magnet or other electric motor 91. This magnet or motor is energized by a battery 92 shown located at the other end of the block. The circuit, including the battery and the magnet 91, is controlled by another magnet 93, this magnet, however, is energized by a track circuit consisting of the wires 94 and 95 connected to the track rail 96 and 97, respectively. Another battery 98 at the other end of the block, is connected between the rails of the respective block, as at 99 and 100. Two circuit closing tongues or armatures 101 and 102, are normally controlled by the magnet 93 and hold the circuit closed, as at 103 and 104, respectively. Two line wires 105 and 106 extend from block to block, supported 70 on poles 107 and cross-arms 108. The wires 105 and 106 are connected by wires 109 and 110 to the contact point 104 and 103, respectively, so that so long as the magnet 93 is energized, the circuit 105 and 106 is closed 75 through the magnet 91 at the remote end of the block, and the semaphore controlled by the magnet 91, at said end of the block, indicates safety. So soon as the locomotive enters the block, however, it short circuits 80 the rails 96-97 and the battery 98 no longer energizes the magnet 93, the result is that the tongues 101 and 102 will leave their circuits 103 and 104, respectively, and open the circuit through the magnet 91, setting the 85 semaphore 90, at the remote end of the block, to danger.

Now, the circuits necessary for my train stopping system operate very well in cooperation with the circuits just described for 90 manipulating the visual signals.

In Fig. 13, I have indicated the circuit shown in Fig. 12, and I have also indicated the additional circuits necessary for my system, in heavy lines, so as to distinguish between the two circuits.

In Fig. 13, I have placed another tongue or an armature 112, to be operated by magnet 93. This armature closes circuit at 113 through a wire 114, which leads to the contact rail 45. I have also included an electro-magnet 115 in parallel circuit with magnet 93, and which controls the three tongues 116, 117 and 118. The magnet 115 is connected to the magnet 93 by the wire 119 and by the 115 wire 120 to the rail 96. The wire 95, shown in Fig. 12, as connected with magnet 93, is disconnected from the rail 97 and connected to the magnet 115. So long as the magnet 115 holds the circuit closed by attracting its 120 armatures, or tongues 116, 117 and 118, maintaining the contacts 121, 122 and 123 closed, the apparatus will indicate safety, and the brake applying mechanism is inert. The circuit necessary for the train stopping 125 130

- apparatus, begins at the rail 97, as at 125, passes through the battery 126 and through wire 127 to contact 123, and over wire 128 to the battery 129. The battery 126 and 129, 5 is split to include this extra circuit and from the battery 129 over the wire 130 to the tongue 117, and contact 122 and through the tongue 112 and wire 114 to the contact rail 45, thus completing the circuit, and so long 10 as this circuit is closed the solenoid 47 will be energized thereby holding the valve 59, in the air line, closed, and the train brakes will not therefore be automatically set. If the circuit just described be open, however, 15 when the shoe 36 is on the contact rail 45, then the magnet 47 will be de-energized, and the brakes will be applied. When the shoe is not on the contact rail 45, it mechanically holds the air valve 59 closed and when it is 20 on the contact rail it withdraws its support from the valve, but the solenoid 47 becomes immediately energized and maintains the valve closed if its circuit conditions are right. 25 The circuit through the magnets 93 and 115 is held closed by the track battery 98, of the preceding block, and so soon as the train leaves that block, magnets 93 and 115 will be re-energized and close contacts 103, 104, 30 113, 121, 122, and 123, thereby re-establishing the circuits of the adjacent block, as shown in Fig. 13.
- The circuit through the contact rail supports is shown more clearly in Fig. 6, is also 35 shown in diagrammatic representation in Fig. 13, energized by a battery 135, which holds the magnet 136 closed. So long as the circuit through this contact rail is perfect, as when the rail supports are unbroken, the 40 solenoid circuit will be closed and controlling its armature 137, the latter will make an electrical connection with the contact 138, thus closing a circuit over the wire 139, to the track rail 97, as at 140, and over the wire 141 to the terminal 142 of the magnet 115 45 and over the wire 143, through the magnet 93, and over the wire 144 to the rail 96, as at 145. This will cause the magnets 93 and 115 to be de-energized and show the visual 50 signal and operate the train stopping mechanism.

The batteries 126 and 129 are split so that either section of the batteries may perform the desired function in the event that either one should become grounded. It will be noticed that the batteries are in series relation when in operation, when the two batteries, and the circuits connected thereto, are in proper condition, they are then capable of energizing the solenoid 47 sufficiently to 60 hold up its armature, or core for the purpose described.

While I have herein shown a single embodiment of my invention for the purpose of clear disclosure, it will be manifest to persons skilled in the art that many changes may be made in the arrangement and disposition of the parts within the scope of the appended claims, and furthermore that the system for automatically stopping the trains 70 may be used in connection with the visual signal or separately.

Having described my invention, what I claim is,

1. A system of the character described, 75 having in combinative association with two locomotives, and in which both locomotives are provided with apparatus to automatically set the brakes by opening the air line; a branch air line extending from end to end, of each locomotive; a valve in each branch line to be automatically opened to stop said locomotive and hand operable valves to cut out the branch air line of either locomotive without interrupting the main line of said 80 locomotive.

2. A system of the character described in combinative association with two locomotives in which both locomotives are provided with an apparatus to automatically set the 90 brakes by opening the air line; a branch air line extending from end to end of each locomotive; a valve in each branch line to be automatically opened to stop said locomotives and hand operable valves to cut out the 95 branch air line at both ends of either locomotive without interrupting its main air line.

In testimony whereof I hereunto subscribed my name.

YORKE BURGESS.
